DESIGN FOR A SHOE

Harry Sobel, Los Angeles, Calif.

Application September 1, 1936, Serial No. 64,678

Term of patent 3½ years

To all whom it may concern:

Be it known that I, Harry Sobel, a citizen of the United States of America, residing in Los Angeles, county of Los Angeles, and State of California, have invented a new, original and ornamental Design for a Shoe, of which the following is a specification, reference being had to the accompanying drawing, forming part thereof.

Fig. 1 is a plan view of a shoe showing my new design.

Fig. 2 is a side elevational view of a shoe as shown in Fig. 1.

I claim:

The ornamental design for a shoe substantially as shown.

HARRY SOBEL.
